UNITED STATES PATENT OFFICE.

STEPHEN I. FEKETE, OF DETROIT, MICHIGAN, ASSIGNOR TO HUDSON MOTOR CAR COMPANY, OF DETROIT, MICHIGAN.

GEARING.

1,164,080.

Specification of Letters Patent. Patented Dec. 14, 1915.

Application filed August 21, 1913. Serial No. 785,846.

To all whom it may concern:

Be it known that I, STEPHEN I. FEKETE, a citizen of the United States, residing at Detroit, county of Wayne, State of Michigan, have invented a certain new and useful Improvement in Gearing, and declare the following to be a full, clear, and exact description of the same, such as will enable others skilled in the art to which it pertains to make and use the same, reference being had to the accompanying drawings, which form a part of this specification.

My invention relates to shifting devices for change speed gearing and an object of my improvements is to provide an improved device in which the operator may adjust mechanism by means of a device conveniently in reach, as in this instance a lever arm at the steering wheel, so that the desired adjustment of the change speed gearing shall be automatically obtained on the movement of a part, in this instance the clutch lever. I secure this object in the device illustrated in the accompanying drawings, in which,

Figure 1, is a side elevation partly in section of a device embodying my invention and so much of an automobile as is necessary to illustrate its connection therewith. Fig. 2, is a plan view of the steering wheel. Fig. 3, is an elevation of the mechanism embodying my invention partly in section, the cover being removed from the casing so that the inclosed mechanism may be seen. Fig. 4, is a section substantially in the line D—D Fig. 3. Fig. 5, is an elevation of the casing containing the mechanism embodying my invention, the cover toward the observer being partly broken away. Fig. 6, is a sectional elevation on the line F—F Fig. 3. Fig. 7, is a detail section on the line G—G Fig. 4. Fig. 8, is a diagrammatic view showing a different relative position of the cam wheels. Fig. 9, is a detail sectional view showing a portion of the mechanism embodying my invention. Fig. 10 is a plan view of a change speed gearing and a mechanism involving my invention connected therewith, the latter being partly broken away.

a is the floor of an automobile body.

b is the dash-board, c is the steering post and d is the steering wheel located at the top of the steering post e.

e is the casing for the change speed gear- 55 ing.

f is the clutch shifting lever having the pedal h at its upper end.

h² h³ indicate different positions of the pedal h, corresponding to different positions 60 of the lever f. The clutch lever f is pivoted at g.

k is a lug extending downward from the pivoted end of the lever f.

i is a casing secured to the side and toward one end of the casing e so as to protrude beyond the right hand end of said casing as shown in Fig. 4.

u is a bearing surrounding an aperture passing through one end of the casing i. 70

s is a rod adapted to reciprocate through the aperture in the bearing u. The rod s is provided with fins t which fit into slots in the walls of said bearing and prevent any relative angular motion of the rod s. Said 75 rod is interposed in the line of travel of the lug k so that if the lever f is turned about the pivot g, it will first come into contact with the rod s and then press said rod into the casing i. 80

m indicate rods by which the gear wheels of the change speed gearing are shifted to provide the adjustments for the different speed ratios. The gear wheels and shifting rods are of an ordinary form and 85 need not be particularly described. They are illustrated in Fig. 10 and the relative position of the shifting mechanism thereto is shown. The rods m-m are forked, as indicated at 14 in Figs. 4 and 9 to engage over 90 the circular cams 13 upon the ends of the shifting lever hereinafter described.

6 is a lug extending inward from the wall of the casing i which is opposite to the wall through which reciprocates the rod s. 95

n² are shifting levers pivoted in parallel planes and coaxially in the lug 6. These levers extend through slots in the casings i and are provided with cams 13 at their outer ends which engage the forks 14 of the 100 rods m-m. The shifting lever n is provided with a lug 4 upon one side of its pivot and 4^a upon the other side; and the lever n² is provided with corresponding lugs 5 on opposite sides of its pivot. 105

o is a partition in the casing i.

p, p are extended bearings integral with the partition o.

5 q, q are springs actuating the rods r, r^2 in a direction away from the partition o . The rods r and r^2 are adapted to reciprocate longitudinally through the bearings p, p and 5 are located at equal distances on opposite sides of the axial line of the reciprocating rod s .

10 w, w^2 are opposite arms of a lever pivoted midway between its ends at v , to the forked inner end of the rod s .

15 x is an arm integral with the lever w, w^2 and extending first at right angles to the arms thereof midway between the ends of the lever w, w^2 then bending outward as shown in Fig. 4 and extending along the outer wall of the casing i, i .

20 y , is a lug extending outward from the outer end of the arm x and engaging in a slot 11 in a wall or portion of the casing i, i .

25 The slot 11 branches at its end farthest from the rod s upward into a branch 11^a and downward into a branch 11^b. The rods r, r^2 bear at their ends opposite to those upon which are fixed the gear wheels z, z^2 , upon the outer ends of the lever arms w, w^2 and are held thereagainst by the springs q, q .

30 z is a gear wheel secured to the end of the rod r remote from the lever w, w^2 , and z^2 is a similar gear wheel similarly located upon the end of the rod r^2 .

35 2 , is an annular cam extending from the free face of the wheel z , concentric therewith, and 3 is a similar cam so extending from the gear wheel z^2 . The teeth of the gear wheels z and z^2 engage with each other so that they shall have proportionate angular movements.

40 12 and 20 are slots in the annular cam 2 , and 21 and 22 are slots in the cam 3 . These slots have a definite angular position about as indicated in Figs. 6 and 7 of the drawings. The annular cams 2 bear against the lugs $4, 4^a$ to hold the lever n in a position approximately parallel to the face of said cam and to hold the corresponding shifting rod m in the position in which its gear wheels are disengaged; the annular cams 3 bear against the lugs 5 and 5^a to hold the arm n^2 in a corresponding position and the other shifting mechanism in its neutral position. If a slot in the annular cam 2 comes opposite one of the lugs 4 or 4^a the other of said lugs will be in position to bear against the cam and the lever n will be 45 brought by the movement of the gear wheel z toward said lever, into a position slanting toward said gear wheel upon the side where the lug comes opposite the slot or cut away portion. The lever arm n^2 may be 50 oscillated in the way just described with reference to the arm n . This is illustrated in Fig. 8 in which it will be seen that the lug 5 on the lever arm n^2 is opposite the slot 22, the lug 5^a being upon the outer surface of 55 the cam 3 . The movement of the wheel z^2

toward the lever n^2 will obviously press upon the lug 5^a and oscillate said lever so that the lug 5 will enter the slot 22. By turning the wheel z^2 until the slot 21 came opposite the lug 5^a , the lever arm n^2 would obviously be 70 oscillated in the opposite direction. So, if the wheel z were moved so that the slot 12 came opposite the lug 4 , the movement of the wheel z toward said lever would oscillate the same in one direction and if the slot 20 were opposite the lug 4^a , the movement of said wheel would oscillate the lever n in the oposite direction.

75 10, is a gear wheel having a broad face, its teeth engaging the teeth of the gear wheel z^2 (Fig. 3).

80 7 is the shaft upon which the gear wheel 10 is keyed. The shaft 7 rests in bearing 8 in a casing 9 which incloses the wheel 10 and communicates with the casing i, i . The shaft 7 (Fig. 1) passes to a position adjacent to the lower end of the steering post c and at this end is provided with a beveled gear wheel 15.

85 16, is a beveled gear wheel, its teeth engaging the teeth of the gear wheel 15. The beveled gear wheel 16 is secured to the lower end of a shaft 18 which extends through the steering post c and is provided at its upper end with a lever arm 17 adapted to pass over a quadrant 19 upon which are placed the indications of the various change speed gear adjustments; thus N stands for neutral, L for low speed, I for intermediate speed, H for high speed and R for reverse.

90 100 The operation of the above described device is as follows: If the lever 17 is turned to the position shown in Fig. 2 registering with the letter N the gear wheels z, z^2 are adjusted through the rod 18, gear wheels 16 and 15, rod 7 and gear wheel 10 so that the cams 3 and 2 are in positions in which the elevated portions of the cams are opposite the lugs $4, 4^a, 5$ and 5^a as shown in Fig. 6, and when the clutch lever h is pressed 110 downward the rod s is pressed in forcing the lever arms w, w^2 against the ends of the rod r and r^2 pressing said rods toward the levers n, n^2 and thus forcing said levers into position approximately parallel to the faces of 115 said wheels (Fig. 4) which corresponds to the neutral position of the change speed gearing. If the lever 17 is turned to register with the letter L on the quadrant 19 the gear wheels z and z^2 are turned through the 120 mechanism above described until the slot 22 is opposite the lug 5 on the lever n^2 . Now if the clutch lever h is oscillated, the rod s is forced inward as before forcing the rods r, r^2 forward. The teeth of the gear 125 wheel 10 and the lever arm n^2 are rocked to the position shown in Fig. 9 thus drawing out the gear shifting rod m with which it engages and throwing in the low speed gear- 130 ing adjustment. In this movement and in

the other movements in which the lever arm n or the lever arm n^2 is oscillated the lever $w w^2$ is turned about the pivot v as indicated in dotted lines in Fig. 5. During the first 5 part of the travel of the rod s the plug y moves in the slot 11 and holds the arm x in its intermediate position. During the latter part of travel of said rod when one of the levers n or n^2 is being oscillated the 10 lever arm $w w^2$ is oscillated as described about its pivot v and the lug y is brought into one of the branches 11^a or 11^b of the slot 11 and engages against the wall of said slot, as shown in Fig. 5.

15 The manipulation of the speeds and the reverse will be obvious from the above description. When the gear wheels $z z^2$ are turned so that the slot 12 comes opposite the lug 4 the lever arm n is oscillated to produce 20 the intermediate adjustment of the change speed gearing. When the slot 20 comes opposite the lug 4^a said lever is oscillated in the opposite direction to produce the high speed adjustment and when the slot 21 comes 25 opposite the lug 5^a the lever n^2 is oscillated to secure the adjustment for reverse motion.

It will be observed that in the above described apparatus when the gearing is moved to its neutral position the rods r and 30 r^2 move at an equal speed and the action is direct and when a gear is moved into engagement with another gear one of said rods is held stationary and the other is moved. The pivotal point of the integral lever arms 35 $w w^1$ changing from the center in the first case to the end of one of said arms in the second case and the power being applied half way between the ends of said arms so that the speed of the moving part is doubled, thus securing prompt engagement and 40 a greater leverage to overcome the frictional resistance to disengagement.

What I claim is:

1. A change speed gearing, an adjusting 45 part therefor, a part adapted to coact with said adjusting part, the last named part being capable of being adjusted independently of said adjusting part to coact with said adjusting part to actuate the same to its neutral or other position.

2. A change speed gearing, an adjusting 55 part therefor, a part adapted to coact with said adjusting part, the last named part being capable of being adjusted independently of said adjusting part to coact with said adjusting part to actuate the same to its neutral or other position, and means for securing said coacting part in its coacting position.

60 3. The combination of a change speed gearing, an adjusting part therefor, a part adapted to coact with said adjusting part, the last named part being adapted to adapt it to actuate said adjusting

part to its neutral or other position and to 65 be reciprocated to cause it to act on said adjusting part.

4. The combination of a change speed gearing, a pivoted adjusting part therefor, a rotatable part adapted to contact said pivoted part upon opposite sides of its pivot, said rotatable part having its surface which contacts said pivoted part at varying distances from the latter, said rotatable part being adapted to be moved toward said pivoted part to engage the same.

5. The combination of a change speed gearing, a plurality of pivoted parts, a plurality of rotative parts, each of said rotative parts being adapted to contact one of said 80 pivoted parts upon opposite sides of its center, said rotatable parts being connected so as to have definite angular relations, the contacting part of each of said rotatable parts being at varying distances from the pivoted 85 part, and means for moving said rotatable parts toward said pivoted parts to engage the same.

6. The combination of a change speed gearing, a plurality of pivoted parts, a plurality of rotative parts, each of said rotative parts being adapted to contact one of said 90 pivoted parts upon opposite sides of its center, said rotatable parts being connected so as to have definite angular relations, the contacting part of each of said rotatable parts being at varying distances from the pivoted 95 part, a lever; said rotatable parts being connected to opposite ends of said lever, and means pivoted to said lever between said 100 connections adapted to force said rotatable part toward said pivoted parts to engage the same.

7. The combination of a change speed gearing, an adjusting part therefor, a part 105 adapted to coact with said adjusting part, the last named part being so constructed and located as to be capable of being rotated and thereby to actuate said adjusting part to its neutral position and to be reciprocated to 110 cause it to act on said adjusting part, and means for automatically securing said rotatable part in its engaged position.

8. The combination of a change speed 115 gearing, a plurality of pivoted parts, a plurality of rotative parts, each of said rotative parts being adapted to contact one of said pivoted parts upon opposite sides of its center, said rotatable parts being connected so as to have definite angular relations, the contacting part of each of said rotatable parts being at varying distances from the pivoted 120 part, a lever, said rotatable parts being connected to opposite ends of said lever, and means pivoted to said lever between said 125 connections adapted to force said rotatable part toward said pivoted parts to engage the same, an arm extending from said lever

and adapted to engage a stationary part when said lever is engaged, substantially as described.

9. The combination of a change speed gearing, a plurality of pivoted parts, a plurality of rotative parts, each of said rotative parts being adapted to contact one of said pivoted parts upon opposite sides of its center, said rotatable parts being connected so 10 as to have definite angular relations, the contacting part of each of said rotatable parts being at varying distances from the pivoted part, a lever, said rotatable parts being connected to opposite ends of said 15 lever, and means pivoted to said lever between said connections adapted to force said rotatable part toward said pivoted parts to engage the same, an arm extending from said lever having a lug toward the outer end 20 of said arm, a guide way for said lug, said guide way being provided with a branch into which said lug is adapted to engage for the purpose described.

10. The combination of a change speed 25 gearing, a plurality of pivoted parts, a plurality of rotative parts, each of said rotative parts being adapted to contact one of said pivoted parts upon opposite sides of its center, said rotatable parts being connected so 30 as to have definite angular relations, the contacting part of each of said rotatable parts being at varying distances from the pivoted part, a lever, said rotatable parts being connected to opposite ends of said 35 lever, and means pivoted to said lever between said connections adapted to force said rotatable part toward said pivoted parts to engage the same, an arm extending from said lever, a lug toward the outer end of 40 said arm, a guide way for said lug, said guide way being provided with a branch into which said lug is adapted to engage and springs tending to return said rotatable parts.

45 11. The combination of a change speed gearing, a plurality of pivoted parts, a plurality of rotative parts, each of said rotative parts being adapted to contact one of said pivoted parts upon opposite sides of its 50 center, said rotatable parts being connected so as to have definite angular relations,

the contacting part of each of said rotatable parts being at varying distances from the pivoted part, a lever, said rotatable parts being connected to opposite ends of said 55 lever, and means pivoted to said lever between said connections adapted to force said rotatable part toward said pivoted parts to engage the same, a spring acting on each of said rotatable parts and tending to return 60 the same.

12. The combination of a change speed gearing, a plurality of pivoted parts, a plurality of rotative parts, each of said rotative parts being adapted to contact one of 65 said pivoted parts upon opposite sides of its center, said rotatable parts being connected so as to have definite angular relations, the contacting part of each of said rotatable parts being at varying distances 70 from the pivoted part, a lever, said rotatable parts being connected to opposite ends of said lever, and means pivoted to said lever between said connections adapted to force said rotatable part toward said pivoted 75 parts to engage the same, and resilient means for tending to hold said lever in its normal position.

13. In a change speed gearing, the combination of parts to be moved into and out 80 of engagement, an actuating means for said parts, said actuating means comprising a differentially moving part adapted to disengage said parts at one rate of motion and to engage the same at a different rate of 85 motion.

14. In a change speed gearing, an actuating mechanism consisting in part of a lever, means for actuating said lever pivoted between the ends of said lever, means whereby said lever shall act at both ends to actuate a moving part of said gearing and shall be pivotally held at one end and adapted to act at the other and to actuate a movable part of said gearing for the purpose 95 described.

In testimony whereof, I sign this specification in the presence of two witnesses.

STEPHEN I. FEKETE.
